UNITED STATES PATENT OFFICE.

BENJAMIN A. BURNS, OF SHELTON, CONNECTICUT.

DESIGN FOR A HANDLE FOR SPOONS OR SIMILAR ARTICLES.

42,123.

Specification for Design.

Patented Feb. 6, 1912.

Application filed September 19, 1911. Serial No. 650,285. Term of patent 7 years.

To all whom it may concern:

Be it known that I, BENJAMIN A. BURNS, a citizen of the United States, residing at Shelton, in the county of Fairfield, State of Connecticut, have invented a new, original, and ornamental Design for a Handle for Spoons or Similar Articles, of which the following is a specification, reference being had to the accompanying drawing, forming part thereof.

The figure is a plan view of a spoon handle, showing my new design.

The design is a creation for applied decoration for a handle for spoons or similar articles.

The design as shown, depicts at the tip end of the handle, an acorn husk from which

tree roots connect. From the said roots, a conventional tree extends through the length of the handle, forming artistic shields by designing symmetrical branches. The branches are tipped along the border and at the bowl end, with foliage. From the roots an acorn nut border is designed along both sides of the handle.

I claim:

The ornamental design for a handle for spoons, or similar articles, as shown and described.

BENJAMIN A. BURNS.
